TAG

Hans F. Stoffel, Scarsdale, N. Y.

Application December 10, 1949, Serial No. 132,370

3 Claims. (Cl. 40—21)

1

The invention relates to tags and more particularly to a tamperproof tag made of a single piece of thin sheet metal adapted to be attached to the stem of a flower or to various other articles.

It is an object of the invention to provide an inexpensive tag that can be bent around the stem of a flower or other thin object and then locked in place by hand without the use of tools and without great force.

Another object of the invention is to construct the tag of a single piece of sheet metal having cupped or dished members or ends arranged to fold upon each other, with means to lock same together when one of the ends is flattened out during assembly operation.

A further object of the invention is to provide means facilitating the removal of the tag, and to provide means to cause breakage of the tag when it is being removed, so that it cannot be salvaged for an unauthorized purpose.

Other objects and advantages of this invention will be apparent from the following description considered in connection with the accompanying drawing submitted for the purpose of illustration and not to define the scope of the invention, reference being had for that purpose to the subjoined claims. In the drawing, where similar reference characters refer to similar parts throughout the several views:

Fig. 1 is a cross-sectional view of the novel tag shown in the open position before it is attached to an article;

Fig. 2 a view looking at the face of the closed tag shown attached to the stem of a flower; and

Fig. 3 a section taken on line 3—3 of Fig. 2.

Before explaining the present invention in detail, it is to be understood that the invention is not limited in its application to the details of construction and arrangement of elements illustrated in the accompanying drawings, since the invention is capable of other embodiments and of being practised or carried out in various ways. Also it is to be understood that the phraseology or terminology herein is for the purpose of description and not limitation.

The tamperproof tag is stamped of a single piece of sheet metal and comprises a circular cup member 10 and a dished disc or flap 11 connected by a band 12, said cup member 10 and flap 11 being arranged to fold upon each other, flap 11 fitting with its peripheral edge or rim inside cup member 10. The cup member has a bottom wall 13, suitable for carrying identifying indicia or advertising matter (not shown), and a curled rim 14 whose peripheral edge 15 is bent

inwardly a short distance to leave a restricted opening through which flap 11 may pass when moved into the dished cup 10. Edge 15 terminates at 16 where band 12 extends from rim 14 to flap 11, forming a loop into which some article to be tagged, such as flower stem 17, may be inserted. Band 12 is provided with reinforcing ribs 18 terminating at 19 whereby bending of band 12 in the closing operation of member 10 and flap 11 is primarily limited to this point, and it therefore may be assumed that the axis about which the cup and flap are folded upon each other passes through this point. By thus fixing the pivotal axis the two members (cup and flap) folded together match exactly so that flap 11 enters freely into cup 10. Flap 11 is dished or curved to be outwardly convex, and it is provided with a plurality of radial slots 20 extending short from the center of flap 11 from the central portion thereof to its outer edge or rim. These slots serve to provide sector pieces therebetween and facilitate flattening out of said sector pieces about respective bendable axes extending between adjacent inner ends of said slots or slits 20. Thus, the diameter of peripheral edge 15 is increased and is moved outwardly. These slots or slits 20 should preferably be in the form of sheared cuts or lines so as not to permit the insertion of a tool intended for tampering. In order to make it easy to discard the seal after it has served its purpose, perforations are provided or a scored line in the band at 21 and 22 where the ribs 18 terminate. Thus the band may be broken off from the tag by bending it back and forth. By making the weakened or scored lines 21, 22 deep enough, it is obvious that the bending required may be reduced to any degree.

In the attaching operation of the tag, the article or, as shown in Fig. 2, the stem of a flower 40 is inserted between band 12 and then flap 11 and cup 10, held between two fingers, are pressed together, whereby flap 11 enters through the opening of cup 10 until the practically straight peripheral edge or rim of flap 11 comes to rest 45 within the space of the curled cup rim 14 and adjacent bottom 13. By compressing the two parts further flap 11 is flattened out so that its outer periphery becomes enlarged to spread under edge 15 and to be permanently locked. It is apparent that to obtain the proper function, the metal must be sufficiently ductile, as too great a 50 resiliency would cause flap 11 to spring back to its original shape.

It is well understood that any additional or auxiliary interlocking or interfitting formations

3

may be arranged, respectively, adjacent the peripheral edge 11 and adjacent the peripheral edge 15 of the curled rim 14, so that in substantially flattened condition of dish-shaped flap part 11 within cup part 10 of the seal a strong and undisplaceable connection between said parts is achieved, which, when tampered with, will be readily deformed and destroyed.

It can thus be seen that there has been provided according to this invention a tamperproof tag stamped of a single piece of sheet metal, comprising a cup with an inwardly curled rim, a band extending from the rim of said cup and terminating in a dished flap arranged to fold upon and proportioned to enter into said cup, and radial slots in said flap to facilitate flattening of said flap to interlock it with said cup.

Having thus described the invention, what is claimed as new and desired to be secured by Letters Patent, is:

Having thus described my invention, I claim:

1. A tag of ductile metal comprising a cup member having a peripheral hollow rim open toward the center of said cup member, a dish-shaped, concave flap connected with said cup member and foldable against the latter, said flap terminating in a peripheral edge provided with radial slits extending from the latter and terminating in inner ends positioned in an area of said flap remote from the center thereof, whereby sector pieces are provided which are bendable about respective axes extending between adjacent

4

inner ends of said slits, said peripheral edge being of a size sufficient to enter said open cup member and when said flap is folded against the latter is caused to straighten out said sector pieces about said respective axes, whereby the diameter of said peripheral edge is increased while said sector pieces are straightened out to less than the largest inner diameter of said hollow rim without being curled in the latter.

5 10 2. A tag according to claim 1, including a band extending from said rim and terminating in said dish-shaped flap for connecting the latter with said cap member, and reinforcing ribs in said band and terminating near the axes about which said cap folds upon said cap member.

15 15 3. A tag according to claim 2, including weakened lines across said band where the latter joins said rim and where said flap is connected to said band.

20

HANS F. STOFFEL.
